DESIGN.

W. L. PHELAN.
WALL CABINET.

APPLICATION FILED DEC. 9, 1915.

49,659.

Patented Sept. 12, 1916.

William L. Phelan, Inventor
By his Attorney, John Shonegan.

UNITED STATES PATENT OFFICE.

WILLIAM L. PHELAN, OF NEW YORK, N. Y.

DESIGN FOR A WALL-CABINET.

49,659.

Specification for Design. Patented Sept. 12, 1916.

Application filed December 9, 1915. Serial No. 66,015. Term of patent 3½ years.

To all whom it may concern:

Be it known that I, WILLIAM L. PHELAN, a citizen of the United States, residing at New York, in the county of Bronx and State of New York, have invented a new, original, and ornamental Design for Wall-Cabinets, of which the following is a specification, reference being had to the accompanying drawing, forming part thereof.

The figure is a perspective view of the wall cabinet, showing my new design.

I claim:—

The ornamental design for a wall cabinet, as shown.

WILLIAM L. PHELAN.

Witnesses:

ALICE ADAMS,
M. E. LOUGHLIN.
